(54) **ADDING MACHINE**

(76) Inventor: **Daniel Kohler**

Daniel Kohler, Shamburg, Pennsylvania.
Letters Patent.

The Schedule referred to in these Letters Patent, and making part of the same, containing a description in the words of the said Daniel Kohler, himself of his improvement in the Machine for Adding.

To all to whom these presents shall come.

Be it known that I Daniel Kohler of Shamburg in the County of Northumberland, and State of Pennsylvania, have invented a New and useful Adding Machine, and that the following is a full and exact description of the construction and operation of the said Machine as invented by me. The said adding machine, or ready, correct and quick calculator, i.e., adds and in some cases subtracts, any numbers or sums, not exceeding several thousands till the particular numbers or sums, thus added amount to one million, and then only noticing the same. It is chiefly thought as one, the quickest and truest instrument yet invented to add numbers, the cargo of a ship, boat, or wagon, and anything of the kind, also it can add Book accounts, amounts of Bills &c; in short it can be used wherever addition is required. It will work so exactly correct that no mistake can be made by itself and a boy who knows the figures from one to 100, and can count 100 can be most allured, the person attending to the machine or instrument, and see from the same, if taught to understand it as well as a clock, the total amount, as quick at any time, of what is in particular added, or counted, as from a clock, the time of the day. To make out, and rectify the machine, and to see the amount, or total of what is added, from the same it must be observed. First, how to make the machine. By seeing a model or drawing of the same you can notice the following viz. The trap wheel and ring are divided in 100 equal divisions corresponding to each other, the divisions on the ring are numbered as 1, 2, 3, 4, 5 &c; to 100, the pushing wheel is sufficiently numbered at every 100 division as seen at 10, 20, 30, &c; this division is sufficient when the

Patented.

Machine is made on a small scale of about five to six inches in diameter, and good when there are only small numbers, or sums not exceeding several hundred and to be added, such as bards, plucks, and the weight of boxes of goods, barrels &c. but for the cargo of ships, boats, both accounts &c. where the sums or numbers exceed several hundred, both ring and wheel are to be divided into 1000 equal divisions corresponding to each other, (i.e.) into 10 grand divisions, as in at 10.20.30.40 each grand division into ten subdivisions making 100 in circumference, and each subdivision into ten sub-subdivisions making 100 in circumference, 100 in one grand division, and 100 in one subdivision. For this division the wheel and ring must be large enough to distinguish the divisions, or so large as the purchaser requires it, but the numbers 1.2.3. 4 &c to 100, are those to be considered as stones, (i.e.) as if there were cyphers added or affixed to them, and the sub-subdivisions between them, as units &c. Both ring and wheel are made of brass, sufficient in strength the ring is engraved on a circular sheet, equal in radius with the breadth of the ring, and radius of the pushing wheel, the circular sheet on which the ring is engraved, has a hole in the center through which a pivot or pinion, from the works under the wheel, and thereto fastened, is extended, to which to the pinion the pushing wheel is fastened, & with it the pushing wheel revolves as pushed. This ring and wheel to which the wheel by a pinion is fastened, and the ring engraved is a plain board of mahogany or other good wood sufficient in thickness fastened at its. 75. by a small hinge, and by a spring and notch at its. 55. so that it can be opened like a watch, and regulated. The ring has a small hand at 10.10, extending over the divisions of the pushing wheel, and at the end, the hand has a small screw. The board to which the above is fastened, has a roomy place for the clock-work under the circular sheet, and at the place where the hands, and face entered when shut, it is cut through, in a circular form, with a glass over it, through which the face and hands are seen, and the amount or total can be taken of what is added, inside, or the clock-work has two plates and posts to hold them together between the plates are two wheel and two pinions, one of the pinions or works in the circular sheet, and a small

allow, the other two, and wheel works in the plates, the three largest wheels have each sixty teeth, the two others, are equal in number, and the pinions each six, the pinion in the sheet drives the largest lower wheel, and which wheel is fixed to the pinion above it, so that it will drive the pinion and longest hand, this pinion drives the next largest wheel, and which drives the one of the middle sized wheel, and last pinion, these two wheels are fixed on this pinion station, and the other middle wheel is driven by the middle wheel, and has the 2nd hand, the largest upper wheel, is driven in driving by the pinion to which the two wheels are fixed, and has the shortest hand, at that end of the plates, where the pinion works in the sheet, is a small piece fixed at the opposite side, is a small lever, at the lower right and left sides of the plate, are on each side such holder through rounder which holds, the plate and clock work can be drawn back, and forward by turning the loose loose from the plate so that it will gear, and ring gear when required, The face is divided into ten equal divisions, and the divisions are numbered 1.2.3.4.5.6.7.8.9.10, the hands revolve on the face when the pushing wheel is pushed, and accordingly as it is pushed or turned, The pushing wheel revolves 10 times until the longest hand, once the longest hand turns around 10 times until the 2nd, once, and the 2nd revolves 10 times until the shortest meets second. It use the machine for adding.

Case 1. When the wheel and ring are divided into 100 divisions, Rule, uncover the small screw, so that it can be pushed easy, and not too easy, then push that division on the pushing wheel, which is opposite the number to be added up against the hand on the outside, if the number exceeds 100, push the units and tens, notice where it stops and turn it totally around as often as they are hundred in the number to be added, Note the wheel is always to be pushed right round and when done adding, it ought to be reversed so that it will remain in that posture, until the total is done.

Example to Rectify the machine, and push the divisions opposite the following numbers, 1.2.3.4.5. with the following 10.11.22.33.44.55.

76. 9. 0. 51. 3. 9. 6. 7. and see this total or amount. (Ans. 16167) and (note) to each total, in the last head, to see the amount. Example. 1. Rectify the machine, and push the following, or add the following, 10. 9. 7. 60. 71. 90. 75. 20. 34. 31. 37. 48. 7. 8. 17. 19. 18. 13. 70. 65. 41. 5. 34. 72. 83. 95. 90. 58. 53. 41. 43. 48. 27. 23. 49. 67. 58. 46. 28. 38. 48. 13. 75. 90. 11. 9. 77. 58. 89. 99. 53. 34. 19. 3. 31. 39. 38. 49. 51. and see the total. (Ans. 2531.) Case 2. when ring and wheel are divided in 1000, divisions or so considered. Rule proceed as in case 1. by viewing and adding, or by pushing, the numbers to be added, and if the number or sum be added exceeds 1000, push the hundreds, tens, and units. Notice, where it stands, and turn it once, totally around for without said in the sum or number given. Example. 315. 600. 770. 860. 110. 110. 230. 1445. 990. 765. 320. 795. 880. 495. 110. 260. 350. 1150. 600. 705. 350. 600. 500. 465. 9100. and see the amount. (Ans. 16167)

Push first 130. Then the pushing wheel has 150. Notice these, and take hold at the little nob or elsewhere and turn it twice around. Thirdly. To rectify the machine;— 1. when the machine is divided into 100 divisions. 1. when there are only a few hundred added. Rule, take hold at the little nob on the wheel or elsewhere, and turn it backwards, or left around until all the hundreds are at 10. & 100, at 110, outside on the wheel, and it is ready for addition. 2nd, when there are units of thousands, and units, and tens of thousands added. Rule, unscrew the outer screw in the hand, push 100 to 110, screw it again, open it at the spring at 10. 25, turn the lever on the steel nut stop with your right hand towards you, draw the block work a little towards the lever, take a hold at the largest wheel next to the lever, with your fore finger move your finger in a shaking manner, by holding it against the wheel, turn the wheel in that manner until all the hundreds are at 10, or near, if near, turn the longest hand to 10, push the block work from you into gear again, turn the lever as it was when made open, shut it & unscrew the little screw at 100, so that it will permit the wheel to turn and not too easy, and the machine is ready for a new addition. 3rd, when the machine is divided into 1000 divisions. 1. When

Here

there are only a few thousand added. Rule, proceed as if there were a few hundred added, see Rule 1. 1. When there are tens of thousands, and tens and hundreds of thousands added, perform what is prescribed under 1. [2] above. (Note) others might begin, known this is sufficient. Fourthly, to see the amount or total of the machine.

Case 1. When it is divided in 100 divisions. — Rule, make places for units, tens, hundreds, units of thousands, and tens of thousands, let the number on the preceding wheel in the units and tens places, that of the longest hand to the left in the hundreds place. That of the 9th on the place of units of thousands, and that of the shortest hand in the place of tens of thousands. i.e., the shortest hand counts tens of thousands. The 2nd, units of thousands, the longest hundreds, and the outer wheel tens and units, and observe to take ciphers for those hands that are not past 1. or pronounced for hands which are past 1. Those units past by them, beginning with the shortest hands and those tens and units on the wheels, and it will be the total, or amount of what is added. Note 4, ciphers on the left are of no value, and when the longest hand only has past one of its units in its revolution, and no other, the others count nothing, and also when the longest and 2nd hand, have past one of the units in their revolution, and the shortest remain below 100th, it will count nothing. 2, when the wheel has 100 at 100, when done adding, the longest will be at one of its units in its revolution, or at 10, if at 10, it will count 0, and the 2nd hand will count its tens, and when the longest hand is at 10—the 2nd will be at one of its revolutions a. at 10. if at 10 it will count 0. and the shortest will count its tens. — likewise when the shortest is exactly at 10, all the other hands will be there also and then the wheel will have 100 at 100, and no superior one in value, will be exactly at one of its divisions, except all the inferiors are at 1, and the wheel has 100 at 100, and when all are full the total will be according to this case 100,000, and according to case 2nd 100,000, and the machine will go on as if started.

anew, or as a clock wheel. - 3, when the wheel has between 90 and 100, the longest hand will appear to be nearly at one of its divisions, but it is not to be put down, that only which it has past last, until the wheel has 100 at 100, or is past 100. Also the 2nd hand will not be at one of the divisions in its revolution until the longest hand is at 10, and until the longest hand is at 10, that number to which the 2nd is near coming to, is not to be put down, that only which it has past last, until as the longest is at 10, or past, and also the shortest hand will not be at one of its divisions in its revolution until the 2nd hand is at 10, and before the 2nd hand is at 10, that number to which the shortest, is near coming to, is not to be put down, that only which it has past last until the 2nd is at 10 or past 10, &c. &c. the whole will regulate each other, and each inferior in value will demonstrate the true epoch and excess of all its superiors. Theorem 1. - Suppose 85 is on the wheel the longest hand has past 8, the 2nd past 6, and the shortest past 8, what is the total. Answer 86,335.

Units	or monomee eight
Tens	6 eight
Hundreds	3 three
Units of 1000	9 thirty and
10 of 1000	5 five.
	<u>86,335</u>

Theorem 2.

Suppose 8 on the wheel longest past 3, the 2nd past 4, but the shortest is past 7, what is the total. Answer 78,360.

Theorem 3. - Suppose the wheel has 100 at 100 the hand is past 4, the 2nd past 9, and the shortest is not past 4, what is the total. Answer 9400. Theorem 4. Suppose the shortest hand has past 8, and none of the others have past 8, but the wheel has 8, how much is it. Ans 86,106. - Case 2. when the ring and wheel are divided in 1000 divisions. Rule. Make places for units, tens, hundreds, units of 1000, 10 of 1000, and 100 of 1000. Let the number of the wheel in the three places on the right viz. in the places.

places of units, tens, hundreds, and that of the longest hand to
the left in the place of units of thousands, that of the 3rd in
the place of 10 of 1000, and of the shortest in the place of 100
of 1000 - or pronounce for the hands as in case 1, and affix
the figures of the wheel for the total.

Note. Cyphers and observations the same as in case 1 to

Witrop

J. P. Shindle

Oscar Bradford

Daniel Kohler.
